APPARATUS FOR THE CONTINUOUS LIQUID TREATMENT OF FLEXIBLE MATERIALS IN STRIP-LIKE FORM HAVING MEANS FOR CONSERVING LIQUID

Jack Howard Coote, St. John's Wood, and Arthur Philip Jenkins, Bloomsbury, London, England, assignors to British Tricolour Processes Limited, London, England, a British company

Application October 25, 1945, Serial No. 624,354

In Great Britain October 26, 1944

4 Claims. (Cl. 95—94)

1

This invention relates to the liquid treatment of materials in strip-like form, such as cinematograph films, ribbons and tapes and more particularly to the provision of improved apparatus for use therein.

Many of the more important recent developments in colour photography involve treatment of photographic film with expensive reagents which, in the form in which they are normally used, are extremely liable to undergo deleterious changes and are thereby rendered useless if they are kept for any length of time. Whilst shallow baths can be used when single positives or short lengths of film are being processed the rapid treatment of long lengths of coloured cinematograph film require the use of baths in which the film can be immersed during travel through the bath if the work is to be carried out at commercially acceptable speeds. This involves the use of large volumes of treating reagents and unless these can be entirely used up before deleterious changes have occurred therein considerable loss of reagent is involved. Some of the most useful of recently developed reagents have an extremely limited life from the point of view of the colour processing laboratory where uniformity and consistency of reproduced colour values under standardized conditions of operation are essential for satisfactory working. It accordingly becomes important to work with the smallest possible bulk of liquid reagent consistent with commercially acceptable processing speeds.

Certain attempts have already been made to deal with this problem. For example, it has been proposed to pass film, supported on an endless band, through a series of vertically arranged flattened tubes in countercurrent relationship to a processing reagent. Such an arrangement is, however, difficult to utilize owing to the fact that it makes no allowance for the reaction of the processing reagent on the endless band neither does it allow for the changes in length produced in the film being processed by the reagent. Changes in the length of film, even though small in themselves, become important when considerable lengths of film are being processed and unless means are provided to allow for increase in length the photographic emulsion may become damaged by contact with the confining walls of the flattened tubes and so be rendered useless. Modern photographic reagents are widely divergent in character and a flexible band capable of indefinitely withstanding an infinite variety of reagents is difficult of procurement. If the band fails while the film is being processed the film is spoiled and rethreading of the apparatus, at any time, is a difficult and time-consuming operation.

It is an object of the present invention to provide improved apparatus for treating strips of film and like materials which is of simple and

2

robust construction, which overcomes the deficiencies of the prior proposals, is extremely economical in the quantity of processing reagent employed, is capable of being used to treat film at relatively high speeds and is readily adjustable for the treatment of both standard and sub-standard films.

According to the present invention apparatus for the liquid treatment of strip-like materials, such as cinematograph films, ribbons and tapes, comprises two elongated tanks, disposed one above the other, the lower tank being a closed tank, means within each tank for guiding said material in strip-like form and two elongated chambers, both in liquid-tight communication with said tanks, of a width small in relation to their length, each of said chambers communicating along the whole of its length with the bottom of the upper tank and the top of the lower tank in the vicinity of the elongated side walls thereof.

According to a feature of the invention one side wall of the lower tank contains one or more apertures, provided with liquid-tight closure means, which afford ready access to the tank: preferably the wall has a single elongated aperture therein.

According to a further feature of the invention the means for guiding strip-like material within each tank is replaceable so that strip-like materials of different widths may be processed.

According to yet a further feature of the invention tensioning means are provided for maintaining the strip material taut where it enters the treating apparatus whilst driving means are provided where the strip-like material leaves the treating apparatus effective to exert a pull on that material.

The present invention provides an apparatus for the liquid treatment of materials in strip-like form which is of simple construction, the operative parts of which are all readily accessible and in the use of which changes in the length of the film during processing are readily accommodated without any tendency for the film to become damaged by contact with the walls of the apparatus.

The invention will now be described with reference to the following drawings illustrating one embodiment thereof and in which:

Fig. 1 is a front view of a film processing tank constructed in accordance with the invention.

Fig. 2 is a vertical section along the line 2—2 of Fig. 1, and

Fig. 3 is a horizontal section along the line 3—3 of Fig. 1.

Fig. 4 is a schematic drawing illustrating the liquid flow.

In the apparatus shown in the drawings an upper tank 1 and a lower tank 2 are in liquid-tight communication the one with the other

through two similar liquid-tight chambers 3 and 4 of substantially the same length as the tanks.

The tanks 1 and 2 are long in relation to their width and to their depth and are of substantially the same length. The upper tank 1 is provided with adjustable screw supports 5 and 6 for supporting a shaft 7A carrying bobbins 7, mounted lengthwise therein and disposed at such a level that the bobbins 7 may be readily submerged in a treating solution. The lower tank 2 is provided with adjustable screw supports 8 and 9 for supporting a shaft 10A carrying bobbins 10 and mounted lengthwise therein. The screw supports 5, 6, 8 and 9 are adjustable so that the shafts and bobbins may be taken out when the apparatus is to be cleaned or exchanged for other bobbins when film of a different width is to be treated. In this way both standard and sub-standard films can be processed in the same apparatus.

The liquid-tight chambers 3 and 4 are of narrow cross-section in relation to their length and are of considerable depth, the preferred depth being substantially greater than the length of the tanks 1 and 2.

The walls of the chambers 3 and 4 are strengthened by horizontal strengthening members 15 which are welded thereto at suitable vertical distances apart. These horizontal strengthening members are symmetrically welded to the opposite walls of the chambers. One or more horizontal supporting members 16 longer than the walls of the chambers 3, 4 and substantially wider than the maximum distance between the outside walls of the chambers 3, 4 are also provided making smooth contact with the walls of chambers 3 and 4 and having their rear edge or edges in contact with the struts 17 upon which the whole apparatus is mounted by means of the mounting screws 18, 18A. The lower tank 2 is further supported by means of the bracket 19 which is mounted upon struts 17 by means of mounting screws 18A. The horizontal supporting members 16 also serve to maintain the chambers 3 and 4 the correct horizontal distance apart. A patch plate 20 is inserted between tank 1 and the struts 17.

The upper tank 1 is provided in the front wall with a socket 21 through which a thermometer or thermocouple may be inserted so that the temperature of the liquid in the apparatus can be observed at any time. The tank 1 may remain open or may be provided with a lid (not shown) having apertures therein through which the film enters and leaves the apparatus.

The lower tank 2 is closed by a dome shaped cover 11 which provides a liquid tight closure thereto and this is supported in the closed position by the locking bar 12 which is locked in position by the wing nut 13. This arrangement enables the lower tank 2 to be readily opened and so permits easy access to the interior thereof and to the bobbins 10 at any time. The tank 2 is mounted upon feet 24.

The bobbins 7 and 10 are of such cross-section as to enable the film to travel through the apparatus without making contact with the walls of the chambers 3 and 4 and are provided with spaced guides 14 between which the coils of film pass during its spiral-like passage through the apparatus.

The inner walls of the apparatus should be smooth throughout. Since the apparatus should be made from material which will not become rough in contact with aqueous solutions it is conveniently constructed from stainless steel or other rust-resisting alloy all joints being made by

welding and the joints on the inside afterwards ground smooth.

At the point at which the film enters the tank there is mounted tensioning means (not shown) i. e. a compensator, by means of which the film is maintained taut during its passage through the apparatus. This may consist, for example, of a sprocket feed, a lightly weighted first pulley and a second pulley.

At the point at which the film leaves the treating apparatus there is mounted a second sprocket or other similar device (not shown) effective to pull the film through the apparatus.

The apparatus is also provided with means which will enable the treating solution to circulate therethrough. An exit point 22 for liquid is provided in the end wall of the upper tank 1 near the point where the film leaves the tank. An entry point 23 for liquid is also provided in the end wall of the lower tank 2. The liquid circuit contains, in addition, a pump for circulating the liquid, means for withdrawing spent liquid, means for admitting fresh liquid, and, if desired, a heat exchange unit. A convenient arrangement is one in which a portion of used liquid is withdrawn between the liquid exit point from the upper tank and the pump while fresh liquid is admitted between the pump and the liquid entry point in the lower tank. The liquid flow circuit is illustrated in Fig. 4 of the drawings.

It will be appreciated that by the use of the two narrow elongated liquid-tight chambers 3 and 4 a great economy is effected in the volume of treating liquid in use at any time. It will of course be understood that any desired strengthening means may be employed to support the narrow, elongated chambers.

The apparatus may be used in the following way for treating film. With the dome-shaped cover 11 in the lower tank 2 open "spacing" (film base material) is threaded through the apparatus, passing, in turn, over the second pulley, over the bobbins 7 in the upper tank downwards, between adjacent spacing guides 14 on the under bobbin 10 in the lower tank 2, then upwards, between adjacent spacing guides 14 and over the bobbins 7 in the upper tank 1 and so continues its spiral-like passage until final emergence from the apparatus whence it passes to the sprocket drive which draws it through the apparatus. At some point prior to reaching the second pulley of the compensator the "spacing" is jointed to the film which is to undergo treatment. This film is drawn from a reel (not shown) by another sprocket driven, thence, about the lightly weighted pulley to the second pulley. The film passes through the apparatus in such manner that the film base is in contact with the bobbins 7 and 10. Since the compensating device maintains the film taut during its travel through the solution the emulsion is positively prevented from coming into contact with any part of the walls of the process-unit and thus prevented from becoming damaged. Film treating solution is passed through the apparatus in counter-current relation to the horizontal direction of travel of the film and at any desired temperature.

It will be evident that the apparatus may also be used to treat numerous other materials in strip-like form such as ribbons and tapes such as cellulose nitrate and cellulose acetate in strip form which are to be dyed or impregnated with liquid compositions. In such cases the sprocket drives are replaced by other means which will serve to pull the strip material from the reel and

through the treating solution. Thus the sprocket drives may be replaced by pairs of normally contacting rollers between which the strip material passes. Obviously the strip material may be made to pass either rapidly or slowly through the treating solution in accordance with the requirements of the particular operation.

Instead of a single cover unit such as the dome-shaped cover 11 the lower tank 2 may be closed in other ways, for example, two separate liquid-tight covers may be provided in the front wall of the tank adapted to be locked in the closed position in any convenient manner.

What we claim is:

1. Apparatus for the continuous liquid treatment of flexible material in strip-like form comprising two horizontally elongated tanks, one disposed above the other, separately removable shafts mounted lengthwise in each of said tanks, each adapted to carry rotatable circular guide means for said strip material, two pairs of side wall members, each pair connected together so as to form an elongated chamber open at the top and at the bottom, each chamber being of small width relative to the width of said elongated tanks the open upper ends of said chambers being directly connected to the bottom of the upper tank by a liquid-tight connection and the open lower ends of said chambers being directly connected to the top of the lower tank by a liquid-tight connection and so disposed as to enclose the greater part of the plane of the direct common tangent of said circular guide means in said elongated tanks to allow the strip-like material to pass between said guide means in spiral-like form without touching the side walls thereof, the lower elongated tank being formed with an elongated aperture in one elongated side wall thereof which extends along substantially that length of said tank which embraces said guide means and having closure means therefor adapted to be removably secured in liquid-tight manner to said wall to close said elongated aperture.

2. Apparatus for the continuous liquid treatment of flexible material in strip-like form comprising two horizontally elongated tanks, one disposed above the other, a shaft removably mounted in the end walls of each of said tanks and having mounted thereon a plurality of separately and freely rotatable bobbins, the lower tank having an orifice for the admission of treating liquid, the upper tank having an orifice for the exit of treating liquid, a pump connected to said orifices for circulating liquid between the two tanks, means for supporting temperature recording means in one of said tanks, two pairs of side wall members, each pair connected together to form an elongated chamber open at the top and at the bottom, each chamber being of small width relative to the width of said elongated tanks, the open upper ends of said chambers being directly connected to the bottom of the upper tank by a liquid-tight connection and the lower ends of said chambers being directly connected to the top of the lower tank by a liquid-tight connection to form an enclosed bath between said upper and lower tanks about the plane of a common direct tangent between said bobbins, the lower tank being formed with an elongated aperture in one elongated side wall thereof which extends along that length of said tank within which are mounted said bobbins and having closure means therefor removably secured in liquid-tight manner to said wall to

close said aperture and locking means to lock said closure means in closed position.

3. Apparatus for the continuous liquid treatment of flexible material in strip-like form comprising two horizontally elongated tanks, one disposed above the other, separately removable shafts mounted lengthwise in each of said tanks and adapted to carry circular rotatable guide means for said strip material, two pairs of side wall members, each pair connected together to form an elongated chamber open at the top and at the bottom, each chamber being of small width relative to the width of said elongated tanks, said chambers and tanks being integrally connected together to form a unitary tank, each of said elongated chambers being so disposed as to enclose the greater part of the plane of a common direct tangent between said guide means to allow the strip-like material to pass between said guide means in spiral-like form without touching said side wall members, the lower elongated tank having an elongated aperture in one elongated side wall thereof along substantially that length of said tank which embraces said guide means and having closure means therefor removably secured in liquid-tight manner to said wall to close said elongated aperture.

4. Apparatus for the continuous liquid treatment of flexible material in strip-like form which comprises two horizontally elongated tanks, one disposed above the other, separately removable shafts mounted lengthwise in each of said tanks and each carrying a plurality of separate, freely rotatable guide means for said strip-like material, two pairs of side wall members, each pair connected together to form an elongated chamber open at the top and at the bottom, each chamber being of small width relative to the width of said elongated tanks, said chambers and tanks being integrally connected together to form a unitary tank, each of said elongated chambers being so disposed as to enclose the greater part of the direct path between the guide means in said tanks and the rotatable guide means in the two tanks being so disposed relative to each other as to provide a free spiral-like path for the material on its passage about said guide means, the lower elongated tank having an elongated aperture in one elongated side wall thereof affording direct access to the guide means along substantially that length of said tank embracing said guide means and having closure means therefor removably secured in liquid-tight manner to said wall to close said elongated aperture and locking means to lock said closure means in closed position.
